United States Patent Office

Des. 178,586
Patented Aug. 21, 1956

178,586

COASTER OR SIMILAR ARTICLE

Joseph M. Vivian, North Bergen, N. J.

Application January 27, 1956, Serial No. 39,945

Term of patent 7 years

(Cl. D44—10)

I claim:

The ornamental design for a coaster or similar article, substantially as shown.
